The ornamental design for a digital logic module for mounting in a control panel, as shown and described.

DESCRIPTION

FIG. 1 is a front perspective view of the digital logic module for mounting in a control panel showing our new design.

FIG. 2 is a left side elevational view thereof.

FIG. 3 is a right side elevational view thereof.

FIG. 4 is a top view thereof, the bottom being a mirror image.

FIG. 5 is a cross-sectional view thereof on an enlarged scale as taken on line 5—5 of FIG. 1.

The rear of the module is substantially flat and unornamented.
